UNITED STATES PATENT OFFICE

RAY E. CHILDS, OF BEIRUT, OKLAHOMA

SAFETY VALVE

Application filed December 28, 1929. Serial No. 417,233.

The present invention relates to safety valves for use in households employing natural gas where the pressure decreases at times sufficiently to extinguish flames and rises after the flame has extinguished so that the gas escapes unless the various valves have been previously cut off which is frequently neglected.

The important object of the invention is to provide a valve of this nature which is exceedingly simple in construction, strong and durable, inexpensive to manufacture, thoroughly efficient and reliable in operation, compact, and otherwise well adapted for the purpose for which it is designed.

With the above and numerous other objects in view, as will appear as the description proceeds, the invention resides in certain novel features of construction, and in the combination and arrangement of parts as will be hereinafter more fully described and claimed.

In the drawings:

Figure 1 is a longitudinal vertical section through the valves embodying the features of my invention, and

Figure 2 is a vertical transverse section therethrough.

Referring to the drawing in detail, it will be seen that the numeral 11 denotes a valve casing with a partition 9 thereacross having the valve seat 12 therein, on which is seatable ball valve 8. An expansion tube rises from the casing 11, in communication therewith at one end and curves over to extend downwardly and has pivotally engaged on its extremity an adjustment arm 2, with which is pivotally engaged a rod 14 which extends down alongside the casing 11.

The arm 2 is pivoted intermediate its ends with the extremity of the tube 1, as is indicated at 15, and is pivotally engaged at one end, as at 16, with a stationary post fixed to the other side of the valve casing and rising therefrom. The arm 2 is connected to the rod 14 by means of the adjustable yoke 17. A lever 4 has an intermediate portion rockable in a bearing 5, and one arm to the outer side of the casing pivotally engaged to the rod 14, and the other arm inside of the cas-

ing, pivotally engaged with the ball valve 8. A thumb screw is threaded through a stuffing box 6, in the bottom of the casing, for the purpose of lifting the ball valve off of the seat 12.

Once the gas goes off, releasing pressure on the expansion tube 1, the ball 8 drops in the seat 12. When the gas comes on again, it enters on top of the ball and holds the same in place, until the ball is released by the thumb screw 7, allowing the gas to enter the expansion tube which raises the ball from the seat and holds the valve open until the gas goes off again, thus eliminating all danger from explosion or death from escaping gas. After the gas comes on and the valve 8 is released by the thumb screw, the operator should always be sure to turn the thumb screw back down so as to be sure of the valve working, the next time the pressure goes off.

I provide a cap 3 threaded in the top of the casing so as to allow access to the interior thereof, and to permit the insertion and removal of the ball valve 8. The advantage of using the ball valve in place of a flat surface valve is that the ball valve operates more efficiently and insures a perfect cut off once it is seated.

Great advantage of this invention resides in its simplicity and capability of being manufactured at a very low cost, so that one of the valves may be used in each household at a minimum amount of expense. It is thought that the construction, operation and advantages of the invention will now be quite apparent to those skilled in this art, without a more detailed description thereof. It is apparent that the changes in the details of construction, and in the combination and arrangement of parts may be resorted to, without departing from the spirit or scope of the invention as hereinafter claimed or sacrificing any of its advantages.

Having thus described my invention, what I claim as new is:

A valve of the class described comprising a casing with a partition having a valve seat therein, a ball valve seatable in the seat, a lever engaged with the ball valve and pivot-

ally engaged in the casing, a rod engaged with the lever exteriorly of the casing, an expansion tube extending from the casing and in communication with the interior thereof, 5 means connecting the rod with the expansion tube, a screw threaded through the casing for unseating the valve, a stationary bar fixed to the casing and extending therefrom, said means for connecting the rod with the expansion tube comprising a lever pivoted on the stationary bar at one end, pivoted intermediate its ends to the expansion tube and pivoted at its other end to said rod.

10 In testimony whereof I affix my signature,
15 RAY E. CHILDS.
